United States Patent Office

Des. 210,642

Patented Mar. 26, 1968

210,642

PORTABLE BURNER

Pierre Eppendahl, Lyon, France, assignor to Societe Anonyme Sidemat, Paris, France, a corporation of France

Filed Apr. 17, 1967, Ser. No. 6,728

Claims priority, application France Jan. 18, 1967

Term of patent 14 years

(Cl. D81—10)

FIGURE 1 is a front perspective view of my portable burner.

FIGURE 2 is a rear elevation view of my portable burner, with the cover omitted for clarity.

The right side of the burner is a mirror image of the left side.

The dominant features of my design are shown in full lines.

I claim:

The ornamental design for a portable burner, as shown and described.
